PANEL MOUNTING STRUCTURE

Albert J. Palfey, Midland, Mich., assignor to The Dow Chemical Company, Midland, Mich., a corporation of Delaware

Filed Nov. 20, 1961, Ser. No. 153,411
6 Claims. (Cl. 20—56.5)

This invention relates to an improvement in panel mounting structures of the window-like type.

The conventional method of installing glazing is to retain the glass in a window sash groove. The four sash sides frame the glass sash; corners are fastened together to complete the assembly. In the alternative, sash grooves may be formed with retaining strips, or stops. The window sash, which may be wood, metal, plastic, or other rigid or semi-rigid material, requires a resilient caulking, or other resilient retainer to separate the sash from the glass to prevent glass breakage due to sash dimensional change, or vibration.

When glazing is installed in a sash, good practice requires allowance of a space, say $\frac{1}{8}$ ", between the peripheral dimensions of the glass, and the sash. Such an arrangement allows the panel, on glazing, to move freely when subject to thermal changes, or structural movement which contacts the sash. This spacing may be filled with a flexible type caulking compound, or an extruded rubber, vinyl, etc. channel gasket.

The present commercially available caulking compounds generally are not entirely satisfactory because the oils, or other components thereof, are often absorbed in wood sash and wood retainers. This presents an undesirable appearance and often causes the wood finishes to fail. Other caulking compounds deficient of oils, or other fluids, may become rigid within a few months after application, thus losing the desired flexibility. Many caulking compounds are extruded from the sash because of glazing expansion. This is not only unsightly, but often the caulking does not return to original position after the glazing has contracted, resulting in cracks and subsequent leakage. Flexible strips used in place of caulking compounds do not generally provide for a permanent tight seal, and foreign material eventually finds its way into the seal and leaks occur. Practically all such seals made of organic materials eventually fail when exposed to the elements, deterioration occurring because of ozone laden air, ultraviolet light rays, solvents used in glazing cleaning compounds, etc.

The panel mounting structures of the present invention represent a distinct improvement over those of the known prior art, and avoid many shortcomings thereof. Briefly, the inventive concept embraces the use of a polyethylene foam gasket which is placed about the periphery of a window assembly, and which cushions the latter when supported in the window sash, or frame. The compressive properties of the gasket are such as to provide full support to the window assembly along the entire load bearing edge, and eliminates the need for lead quarter point supports. In addition, the gasket may be re-used if necessary, or desired. A sealant is used to protect the gasket from the atmosphere, moisture, dirt, dust or other undesired foreign matter. The sealant has excellent adhesion properties relative to wood, glass, metal and most other materials. However, when applied to polyethylene foam there is no bonding effect, thus allowing a certain degree of movement of the window assembly within the supporting sash, or frame without distortion of the gasket.

The main object of the invention is to provide an improvement in panel mounting structures of the window-like type.

2

A more specific object is to provide a panel mounting structure in which a window assembly is protected against vibration, expansion, shock and frame shifting.

A further object is to provide a panel mounting having a sealant which allows a certain degree of movement of the window assembly within the supporting sash, or frame, without distortion of the gasket.

Still another object is to provide a panel assembly which will withstand the elements, and will not deteriorate because of ozone laden air, ultra-violet light, solvents used in glazing cleaning compounds, and other causes.

A further object is to provide a window assembly including a frame, or sash support, made of wood, metal or other materials, having an improved final appearance.

These and further objects and features of the invention will become more apparent from the following description and accompanying drawings wherein:

FIG. 1 is a fragmentary perspective view of a panel assembly illustrative of an embodiment of the invention;

FIG. 2 is a section view of a modified panel assembly incorporating the principles of the invention;

FIG. 3 is a section view of a window assembly embodying the principles of the invention;

FIG. 4 is a section view of another window assembly embodying the principles of the invention;

FIG. 5 is a fragmentary side view of the window assembly of FIG. 4;

FIG. 6 is an enlarged exploded perspective-like view illustrating details of construction as used in the FIG. 4 assembly;

FIG. 7 is a section view of a further modification embodying the principles of the invention;

FIG. 8 is a graph showing typical stress-strain curves, and showing also recovery from initial compression, of a gasket material used in window assemblies embodying the principles of the invention; and

FIG. 9 to FIG. 14, inclusive, illustrate cross-section views of various gasket forms used in window assemblies embodying the principles of the invention.

Referring now to the drawings and more particularly to FIG. 1, a panel, or window-like assembly 20 is illustrated which includes a pane of glass 22 supported in parallel relation to a similar size sheet of wood, or hard board 24, on which written matter 26, or other information may be carried. If desired, a pane of glass, or other material, may be substituted for the board 24. The elements 22 and 24 are maintained in spaced relation by a metal tubing 28 having openings 29, which tubing 28 commonly is made of aluminum, and which has a silica gel filling 30. The latter absorbs any water vapor trapped between the elements 22 and 24. A space is provided between the outer edge of the tubing 28 and the peripheral edge of the elements 22 and 24, which space is filled with a sealant 32. While various types of sealant may be used, the inventive concept embraces the preferred use of a sealant identified as No. 780, made by the Dow Corning Corporation. The specified sealant is an uncured silicon rubber with an acid hardener, such as acetic acid, the combination of which, when brought into contact with moisture in the surrounding atmosphere, results in a curing of the rubber. The advantages of the specified sealant are: it provides a single component system, and is available in caulking cartridges ready for use; it has superior adhesive properties relative to glass, wood and metal; and, it has excellent resistance to climatic conditions, i.e., temperature and ultra-violet light. The peel strength of the No. 780 sealant is approximately 20 lbs. per sq. in. upon glass, metals or wood. The panel assembly thus formed, is surrounded by a compressible U-shaped gasket 34, which is adapted to support the panel assembly in a frame

means consisting of a sill, or sash 36 and a pair of retaining strips 38, secured to the sill by fastening means, such as screws 40. While the frame means is illustrated as being made of wood, any other construction material may be utilized as desired.

The gasket 34 may be formed of various compressible materials, however, the inventive concept embraces the preferred use of an extruded polyethylene foam produced by the Dow Chemical Company, and identified by their registered trademark "Ethafoam." The physical properties of the specified gasket material are fully set forth in the Company Bulletin 171-125A. The graph of FIG. 8 illustrates a typical stress-strain curve (compression rate of 20 inches per minute) of "Ethafoam"; the area enclosed by the hysteresis loop gives the percent work energy loss at a particular degree of compression. The advantages of the specified gasket material are: it is relatively low in cost; has a closed cell structure, hence does not absorb, nor is wetted by water; easy to handle; non-toxic and odorless; low density (1.8 to 2.2 lbs. per cu. ft.); low thermal conductivity (K factor=0.35 B.t.u.'s./hr. ft.² in °F); good ozone resistance; good solvent resistance; and can be extruded in continuous strips, and be wound on a reel.

Two similar spaces, defined by an outer edge of the gasket 34, an outer side of the pane 22 and the board 24, and an inner side of a strip 38, are filled with the sealant 32. A further characteristic of the sealant 32, i.e., No. 780, which makes it especially suitable for the present purposes, is that it does not bond to polyethylene, thus allowing certain parts of the panel assembly a certain degree of movement without distortion.

In fixing the strips 38 in position, the gasket 34 is compressed between the strips 38 to a thickness of approximately $\frac{1}{16}$ ". Glass in window assemblies is conventionally supported at base quarter points to assure support, especially in installations of large size. The $\frac{1}{4}$ " thick lead blocks customarily used to support insulating glass, may be eliminated when using the teachings of the invention. An irregular base support may cause the glass to bear at a single point, which may result in glass failure when subject to forces such as building movement, moisture expansion of wood, etc. The gasket 34 will provide for continuous glass support along the entire length, thus eliminating the danger of glass failure as associated with conventional installation methods.

The gasket 34 can readily carry loads generally encountered in large window installations. For example, a double glazed window 48" wide by 72" high by 1" thick weighs about 157 pounds. Such a window will produce a unit pressure of 3.28 lbs. per sq. in. on the supporting base. Referring to the curve in FIG. 8, it will be seen that such a load will cause less than 5% compression of the gasket.

The modified forms shown in FIGS. 2 to 7 inclusive, represent how the principles of the invention may be used in different panel or window arrangements.

In FIG. 2, an arrangement is shown wherein two panels 44 of material similar to "Masonite," are used for a wall construction, such as in a house trailer. A roof portion 46 is formed to provide a skirt 48 against which the panel assembly is urged by an L-shaped member 50 secured to the roof portion by fastening means, or welding, as the case may be. The panels 44 are maintained in spaced relation within the peripheral opening defined by the skirt 48 and member 50, by means of the metal tubing 28 containing a silica gel filling 30, and having openings 29. The gasket 34, of extruded polyethylene foam, surrounds the peripheral edge of the panel assembly and maintains the panels 44 in spaced relation to the skirt 48, the member 50, and the inner surface of the roof portion 46. Sealant 32, preferably that previously identified as No. 780, is applied in the peripheral space defined between the inner surfaces of panels 44, the gasket 34, and an exterior surface of the tubing 28. The same type of sealant 32 is

applied in the peripheral spaces defined by the exterior surfaces of the panels 44, the gasket 34, skirt 48, and member 50.

The embodiments shown in FIGS. 3 to 7, utilize the same type of compressible foam and sealant arrangements as described in connection with the embodiments illustrated in FIGS. 1 and 2. For the purpose of brevity, these will be briefly described using the same numerals for like parts as used in the FIGS. 1 and 2 embodiments.

The arrangement shown in FIG. 3 illustrates the manner in which a double pane window assembly 52 is arranged on an outside sill member 54, with a removable inside sill member 56 compressing the gasket 34, and holding the assembly 52 in position upon the sill member 54.

In FIG. 4 a double pane insulating window assembly 58 is supported in a wooden frame or sash assembly 60, having a groove 62 for receipt of the assembly 58. The elements forming the sash assembly 60 may be mitered at each end, as best seen in FIG. 5. A masking tape 64 may be employed at each corner to hold the gaskets in position upon the assembly 58 prior to installation in the frame assembly 60, as illustrated in FIG. 6.

FIG. 7 illustrates a double pane insulating window assembly 66 wherein the side extensions, or legs of the gasket 34, are unevenly compressed by application of retaining strips 68 having tapered inner wall portions 70. The strips 68 are secured to a sill, or frame member 72, by fastening means such as screws 74.

The material from which the gaskets are made, preferably "Ethafoam," may be compressed 50% with about 15 lbs. per sq. in. load. This force may be greater than desired to compress a window gasket to such a degree with retaining strips. Other shapes may be readily extruded, as illustrated in FIGS. 9 to 14, which would require a relatively small load to place the retainer strip in position against the sides of the gasket.

In FIGS. 12 and 13, the dashed lines indicate the cross-section shape after installation, while the form shown in FIG. 14 is for use where there is to be no compression on the side legs of the gasket.

The foregoing description has been given in detail without thought of limitation since the inventive principles involved are capable of assuming other forms without departing from the spirit of the invention or the scope of the following claims.

What is claimed is:

1. In a panel mounting structure having a sheet-like element supported in a groove means of a frame, a resilient gasket extending around the periphery of the sheet-like element for support within the groove means of the frame, and a sealant extending about the sheet-like element and inwardly spaced from its periphery in engagement with a wall of the groove means, the gasket, and the sheet-like element, said sealant being non-adhering to said gasket but being adhesively bonded to the sheet-like element and the groove means of the frame.
2. In a panel mounting structure having a window assembly supported in a groove means of a frame which extends about the window assembly, a U-shaped polymeric foam gasket extending around the periphery of the window assembly for support within the groove means of the frame, and a sealant extending about the window assembly and inwardly spaced from its periphery in engagement with a wall of the groove means, the gasket, and the window assembly, said sealant being non-adhering to said gasket but being adhesively bonded to the window assembly and the groove means of the frame.
3. In a panel mounting structure having a window assembly supported in a groove means of a frame which extends about the window assembly, a U-shaped polyethylene foam gasket positioned about the periphery of the window assembly for support within the groove means of the frame, said window assembly being arranged in said groove means to form a space between the edges of the gasket legs and the sides of the window assembly as well

as the walls of the groove, and a sealant within said space which sealant is non-adhering to the gasket but which forms a bond with the window assembly and a wall of the groove.

4. In a panel mounting structure including a pair of panel elements positioned in parallel spaced relation and a sash means formed to provide a peripheral groove for receipt of said panel elements, a spacer means positioned between the panel elements, a U-shaped polyethylene foam gasket arranged in said groove for support of the panel elements, and a sealant arranged between the spacer means and the panel elements, said sealant also being arranged between the edges of said gasket and the sides of said groove, said sealant being non-adhering to said gasket.

5. In a panel mounting structure including a pair of panel elements positioned in parallel spaced relation and a sash means formed to provide a peripheral groove for receipt of said panel elements, a metal tubing positioned between the panel elements and about the periphery thereof, said tubing being open to the volume between the panel elements, a U-shaped polyethylene foam gasket arranged

in said groove for support of the panel elements, and a sealant between the tubing and the panel elements, said sealant also being arranged between the edges of said gasket and the sides of said groove, said sealant being non-adhering to said gasket.

5 6. A tubing according to claim 5, wherein said tubing is filled with silica gel.
